(57) CLAIM

The ornamental design for a desk, as shown and described.

DESCRIPTION

FIG. 1 is a perspective view of a desk according to this invention;

FIG. 2 is a front view of the desk shown in FIG. 1;

FIG. 3 is a left side view of the desk shown in FIG. 1, the right side view being a mirror image thereof;

FIG. 4 is a rear view of the desk shown in FIG. 1;

FIG. 5 is a top view of the desk shown in FIG. 1; and,

FIG. 6 is a bottom view of the desk shown in FIG. 1.

The broken lines in the drawings depict portions of the desk that form no part of the claimed design.

1 Claim, 6 Drawing Sheets
